UNITED STATES PATENT OFFICE.

DAVID BUSCH, OF WASHINGTON, DISTRICT OF COLUMBIA.

ADJUSTABLE BAKING-RING.

1,110,882.

Specification of Letters Patent.

Patented Sept. 15, 1914.

Application filed February 24, 1914. Serial No. 820,551.

To all whom it may concern:

Be it known that I, DAVID BUSCH, a citizen of the United States, residing at Washington, District of Columbia, have invented 5 certain new and useful Improvements in Adjustable Baking-Rings, of which the following is a specification.

This invention relates to a new and useful improvement in rings for baking biscuits, cakes, muffins and similar articles, and 10 its object is the production of an adjustable ring, which may be varied within the limits of the largest and smallest sizes of which the device is capable.

15 The invention consists primarily in an adjustable baking ring.

In the drawings: Figure 1 represents a top view of the device at the outer limit of adjustment. Fig. 2 represents an edge view. 20 Fig. 3 represents a top view of the device at the inner limit of adjustment.

In these drawings: the numeral 1 designates a single strip having parallel edges and made of elastic material continuously 25 plain and smooth on both surfaces, having the same width throughout and adapted to be used as a ring for baking biscuits, cakes, muffins, etc. At the ends 2 and 3 of this strip 1 there are loops 4 and 5. The body 30 of the strip passes through these loops 4 and 5 so that the strip 1 is slidable through both loops. One loop 4 has a binding screw 6 passing into it so as to bind against the strip 1.

35 If desired the strip may have on its surface a scale 7.

In use, the ring is made of any desired size within the limit of its movement upon itself. It may be opened to the largest size, 40 as shown in Fig. 1, or compressed to the smallest size as shown in Fig. 2. The loops 4 and 5 hold the ends of the strip and also limit the outer and inner movement of adjustment. Within these limits, the strip is 45 adjustable. The sizes may be varied to suit any amount of change. With the scale the strip may be adjusted to any determined size. While the binding screw 6 may be useful, it is not essential as the elasticity of

the strip will bind it sufficiently against the 50 loops so as to prevent any unintentional changes in the size of the ring.

This elastic strip passing through these loops is held therein in any adjustable position by the pressure of the strip upon the 55 loops. This produces a baking ring having plain smooth faces throughout its entire length and without any attachments thereto, being like the ordinary baking ring, except that it is adjustable. The ends are held to 60 the strip forming the ring so that it is a complete ring without any liability of an end catching into anything. With such an invention applied to baking rings the number of these rings to be carried by an establishment will be very sensibly diminished. 65 There need be in stock only enough to bake articles of one size. Because the rings may be adjusted for any size and after one size is cooked, the rings may be adjusted for another size. This device not having any bottom is to be placed upon a suitable baking pan. According to the size of the baking pan, as many rings as desired may be used, and of different sizes, thus baking different 70 sized cakes with the same heat. The strip is of uniform size and has parallel edges without having any projections beyond the edges. The ring is cylindrical and will be flat on the pan upon whichever edge the 75 strip be placed. And it may be used with either edge down.

Having described my invention, what I claim is:

A cylindrical baking ring consisting of a 85 single uniform strip of elastic material, having parallel edges and continuous smooth faces, and at each end a loop, the strip passing through these loops, the strip bearing against the loops, adjustable therethrough, 90 and held in adjustable position by the pressure upon the loops.

In testimony whereof I affix my signature in presence of two witnesses.

DAVID BUSCH.
